Ogza. L. Miller of Charleston South Carolina
Letters Patent

The Schedule referred to in these Letters Patent and making part of the same contains -
ing a description in the words of the said Ogza L. Miller himself his improvement
in the mode of increasing the adhesion of the driving wheels of the Locomotive
Steam Engine.

To all to whom these presents shall come.

Be it known that Ogza L. Miller of the City and District of Charleston State
of South Carolina have invented a new and useful mode of increasing the adhesion of
the driving wheels of the Locomotive Steam Engine on Rail Roads by using the tender
or car near the Engine for the purpose of adding weight to the driving wheels of
the Engine at such times only, as a greater adhesion is required than the weight
would give which it would be practicable to carry as a fixed weight on those
wheels without injury to the road. At the points of starting and on the
ascents where increased adhesion is required. I attach part of the weight of
the car or tender which is near the engine to the end of the frame of the car
near the driving wheels which may be done by means of a screw, screw, wedge
or pulley, and detach it again when the increased adhesion is no longer nece-
sary. The mode which I have used and found to answer perfectly in prac-
tice is simply to connect the car or tender near the Engine by a strong iron
bar, or lever one end of which is bolted to the under side of a cross timber
in the frame of the car or tender, the other end of which lever
extends under the frame of the tender to the end of the frame of the engine and onto
the iron which together with the driving bolt secures it to the engine.

Transversely to this lever, I attach to the end of the tender near the engine two
levers, so that their fulcrums shall be six or eight inches on each side of
the main lever, or driving bar. These levers have a jaw or pivot six or
six inches in length directly over the main lever, and should be about 4 1/2
feet in length. When the increased adhesion is wanted, the Engineer
has, only to place his foot upon the ends of those levers and press them in
to a hook or groove so that, pressure on the corner post of the tender and a
portion of the weight of the car or tender near the engine is thus thrown
upon the driving wheels of the engine, and when the increased adhesion

8273 X

as one longer wanted. This weight is detached by simply loosening the end of the lever. What I claim as my invention is the making use of the lever to tender most the engine for the purpose of increasing the adhesion of the driving wheel of the locomotive steam engine at those points where more adhesion is required than the weight would give which it is eligible to carry as a fixed weight on these wheels. Whether the same be effected in the mode above described or any other which attains the same end.
